R. W. SIMON

DANDELION PICKER

Filed Dec. 9, 1922

Inventor

R. W. Simon.

By Arthur H. Stenger.
Attorney

UNITED STATES PATENT OFFICE.

RICHARD W. SIMON, OF OMAHA, NEBRASKA.

DESIGN FOR A DANDELION PICKER.

Application filed December 9, 1922. Serial No. 4,539. Term of patent 3½ years.

To all whom it may concern:

Be it known that I, RICHARD W. SIMON, a citizen of the United States, residing at Omaha, in the county of Douglas and State of Nebraska, have invented a new, original, and ornamental Design for a Dandelion Picker, of which the following is a specification, reference being had to the accompanying drawing, forming a part thereof.

The figure is a plan view of a dandelion picker showing my new design.

I claim:

The ornamental design for a dandelion picker, as shown.

In testimony whereof, I have affixed my signature in presence of two witnesses.

RICHARD W. SIMON.

Witnesses:

HIRAM A. STURGES,
ARTHUR H. STURGES.
